Primary Examiner—Holly Baynham*Assistant Examiner*—Robin V. Taylor*Attorney, Agent, or Firm*—Richard B. O'Planick; Lisa B. Riedesel[57] **CLAIM**

The ornamental design for a rim for laundry basket, as shown and described.

DESCRIPTION

FIG. 1 is a top right front perspective view of a rim for laundry basket showing my new design. The broken line showing of a bottom portion of a laundry basket is for illustrative purposes only and forms no part of the claimed design;

FIG. 2 is a top plan view thereof;

FIG. 3 is a front elevational view thereof; the rear elevational view being a mirror image;

FIG. 4 is a right side elevational view thereof; the left side elevational view being a mirror image; and,

FIG. 5 is a bottom plan view thereof.
